UNITED STATES PATENT OFFICE

2,583,107

SASH CONSTRUCTION

Walter M. Krantz, Youngstown, Ohio

Application February 9, 1948, Serial No. 7,205

2 Claims. (Cl. 189—76)

1

This invention relates to a double hung storm sash and more particularly to the type of storm sash in which glazed sash are interchangeable with screen sash.

A further object of the invention is the provision of a double hung storm sash construction.

A still further object of the invention is the provision of a novel means of assembling a mounting frame for a sash positioned therein.

A still further object of the invention is the provision of an improved and simplified storm sash frame construction wherein a plurality of modifying sections are joined to a main frame section to adapt the same for the reception of double hung sash.

This application is a continuation-in-part of my co-pending patent application on storm window frame Serial No. 681,245, filed July 3, 1946, now Patent Number 2,504,700.

In the above mentioned co-pending patent application, Serial No. 681,245, there is disclosed a storm window frame and several modifying sections and means for positioning and retaining these modifying sections in the said frame. The present invention relates to the same construction with the exception of the means for retaining the modifying sections in the storm window frame.

In the aforementioned co-pending patent application, wedge members were employed to distort longitudinally extending fins on the frame to engage and retain the modifying frame members positioned therein. In the present disclosure the wedge members are eliminated and a wrench is used for simultaneously distorting oppositely disposed longitudinally extending fins of the main frame into position abutting and holding the modifying frame sections therein.

It is well known in the art that many and various storm window constructions have been proposed, a number of which have utilized extruded metal shapes and have of necessity required a number of interengaging pieces to define suitable areas for the reception of glazed sash positioned therein. The present invention relates to a simplified double hung storm sash and more particularly to the means employed in assembling the several component parts thereof and locking them in assembled position to form the completed frame.

With the foregoing and other objects in view which will appear as the description proceeds, the invention resides in the combination and arrangement of parts and in the details of construction hereinafter described and claimed, it

2

being understood that changes in the precise embodiment of the invention herein disclosed can be made within the scope of what is claimed without departing from the spirit of the invention.

The invention is illustrated in the accompanying drawing, wherein:

Figure 1 is a front view of a storm sash.

Figure 2 is a vertical cross section taken on line 2—2 of Figure 1.

Figure 3 is a vertical cross section taken on line 3—3 of Figure 1.

Figure 4 is a horizontal cross section taken on line 4—4 of Figure 2.

Figure 5 is a vertical cross section taken on line 5—5 of Figure 1.

Figure 6 is a cross section of a portion of the storm window frame and illustrating a deforming wrench in position therein.

Figure 7 is a horizontal cross section taken on line 7—7 of Figure 6.

By referring to the drawings and Figures 1 and 2 in particular it will be seen that a double hung storm sash has been disclosed in position on a window casing 10, the sill 11 thereof supporting the lower portion of the double hung storm sash and the exterior portion of the double hung storm sash overlapping the casing 10.

The double hung storm sash comprises a main frame of rectangular shape to match the window opening in which it is installed and is formed of three extruded metal shapes. The side sections 12 of the main frame are formed of one extruded shape as shown in enlarged cross section in Figure 4 of the drawings. The top section 13 of the main frame is formed of a different extruded metal shape, as shown in Figure 3 of the drawings, and the bottom section 14 of the main frame is formed of a still different extruded metal shape, as shown in Figure 5 of the drawings.

Each of the three extruded metal shapes 12, 13 and 14 has an extending surface flange, an edge of which is adapted to overlie the window casing 10, and each of the extruded metal shapes 12, 13 and 14 have longitudinally extending T-headed ribs 15, 16 and 17, respectively, it being observed that the T-headed formation on the ribs 15 and 16 are similar in size and shape while the T-headed formation on the rib 17 includes an inwardly extending offset flange 18. The extruded metal shape 12 from which the vertical side sections of the main frame are formed has a pair of longitudinally extending, inwardly turned flanges 19 and 20 which are adapted to

be distorted at intervals as illustrated in Figures 6 and 7 of the drawings and hereinafter described in order to retain modifying shapes 21 and 22 in the side sections of the main frame to define vertical channels in which double hung sash 23 and 24 may be positioned. It will be observed that the sash 23 is normally located in lower inner position in the main frame and slideable vertically therein in the channel defined by the modifying shape 22 heretofore referred to. The upper outer sash 24 is positioned in the main frame so that it rests on the upper ends of the modifying shapes 21, the upper ends being indicated by the numeral 25 in Figure 2 of the drawings.

The extruded shape 13 is similar to the extruded shape 12 with the exception that it has a single longitudinally extending flange 26, the outermost edge 27 of which is inwardly turned and this section is used as the upper most portion of the rectangular main frame and forms, in conjunction with the flat surface flange of the shape 13, an area for the reception of the upper edge of the upper outer sash 24. The lower section 14 of the main frame is similar in overall appearance to the extruded shapes 12 and 13 heretofore described and includes a surface flange with an inturned auxiliary flange 25 formed thereon replacing, in effect, the modifying shape 21 heretofore referred to in connection with the side sections 12 of the main frame. The T-headed extension has the additional flange 18 formed thereon which defines with the rest of the shape a transverse channel for the reception of the lower edge of the lower inner sash 23. It will thus be seen that by utilizing the distortable flanges 19 and 20 of the extruded shape 12 the modifying shapes 21 and 22 may be locked into permanent engagement with the shape 12 and thereby form vertical side rails of the main double hung storm sash frame suitable for receiving the sash 23 and 24 in double hung relation therein.

It will also be observed that the sash 23 which is the inner lower one of the two sash is slideable vertically so that it can be opened for ventilation. The sash 24 is not slideable vertically but is positioned in more or less fixed relationship in the upper outer half of the frame with its upper end in engagement with the upper extruded section 13 as heretofore described. Its lower edge rests on the upper ends 21A of the modifying shapes 21.

In substituting a screened sash for the sash 23 it is lifted vertically until positioned in the upper half of the frame from whence it may be directly removed. As the modified members 22 extend vertically only approximately one-quarter of the total vertical distance of the main frame.

By referring to Figures 6 and 7 of the drawings the means of positioning the modified shapes 21 and 22 in the frame may be seen and by referring thereto it will be observed that a wrench 28 has been illustrated which includes an offset portion 29 and a handle 30 and has a head comprising a pair of offset shoulders 31 formed in

axial alignment with the handle 30 of the wrench 28. The wrench 28 is employed in distorting the flanges 19 and 20, as illustrated herein, and is positioned with the offset shoulders 30 in longitudinal alignment with the flanges 19 and 20 and then turned as by moving the wrench 28 one-quarter of a revolution thus bringing the offset shoulders 31 into crossways position where they force the flanges 19 and 20 away from one another and into engagement with the modifying shapes 21 and 22 heretofore referred to. When this operation is performed at intervals as shown in Figure 7 of the drawings, the modifying shapes 21 and 22 are securely locked in permanent engagement in the frame. This method of modifying the main double hung storm sash frame is inexpensive and practical and results in an attractive weather-tight construction particularly adapted for storm sash constructions.

It will thus be seen that a double hung storm sash has been disclosed which includes a main frame of lip-type capable of overlying the casing 10 of a dwelling house window, for example, and capable of receiving therein the sash 23 and 24 or the sash 24 and alternate screen sash replacing the sash 23. The window is capable of relatively inexpensive fabrication and assembly and it will be observed that it includes a sash construction novel in the art and set forth in my co-pending patent application Serial No. 693,275, filed August 27, 1946, Patent No. 2,505,553, issued April 25, 1950, on Glass Framing Construction.

Having thus described my invention, what I claim is:

1. Frame element construction for storm window comprising: a body member including a U-shaped channel; a pair of ribs extending from the web of said U in substantially the same direction as the flanges thereof to form three parallel channels; a modifying member in each of the outermost of said channels and adapted to receive the sash of said storm window, said modifying members each having a shallow groove along that side thereof which faces the other modifying member and adjacent the free edges of said ribs, said ribs being substantially parallel with each other throughout the major part of their respective lengths and having a plurality of independent offset portions of each thereof extending out from the plane of each of said ribs toward the respective mutually adjacent modifying members and into the said respective shallow grooves thereof for locking said modifying members to said body part.

2. The article described in claim 1 wherein said offset portions are opposite each other.

WALTER M. KRANTZ.
